Filed Feb. 6, 1967, Ser. No. 5,701

Term of patent 3½ years

(Cl. D87—2)

Fig. 1.

Fig. 2.

Fig. 4.

Fig. 3.

FIG. 1 is a perspective view of a handbag closure hasp showing my new design.

FIG. 2 is a top edge plan view thereof, the broken line showing of the top of the design having been omitted for convenience of illustration.

FIG. 3 is a front elevational view thereof, and
FIG. 4 is an end elevational view thereof.

The dominant features of the design reside in the full line portions of the drawing.

The rear elevational view is the same as the front elevational view except that the surface ornamentation around the square central opening is omitted.

I claim:

The ornamental design for a handbag closure hasp, substantially as shown and described.
